UNITED STATES PATENT OFFICE.

JAMES P. MORLEY AND GEORGE W. KITE, JR., OF CHICAGO, ILLINOIS, ASSIGNEES TO
BASTIAN-MORLEY CO., OF CHICAGO, ILLINOIS, A CORPORATION.

GAS-BURNER.

1,257,010.

Specification of Letters Patent. Patented Feb. 19, 1918.

Application filed August 25, 1917. Serial No. 188,170.

To all whom it may concern:

Be it known that we, JAMES P. MORLEY and GEORGE W. KITE, Jr., both citizens of the United States, and residents of Chicago, in the county of Cook and State of Illinois, have invented certain new and useful Improvements in Gas-Burners for Water-Heaters and the like, of which the following is a specification.

10 The present invention relates to gas burners of the type shown in U. S. Letters Patent No. 1,072,072, which were granted September 2, 1913 to Bastian-Morley Co., as the assignee of William B. Bastian.

15 Generally stated the object of the invention is to provide a burner of the type referred to of improved construction—improved particularly with regard to its efficiency; the means for holding it in proper 20 position with relation to the pipe or other device by which it is supported and which passes through it centrally; and its simplicity and consequent cheapness of construction.

25 To these ends the invention consists in the features of novelty that are hereinafter described with reference to the accompanying drawings which are hereby made a part of this specification and in which:

30 Figure I is a sectional elevation on a small scale of the lower portion of a water heater such as is shown in the patent aforesaid, with the improved burner applied thereto, the burner being viewed from the rear side.

35 Fig. II is a plan view of the improved burner of the preferred form and on a larger scale.

40 Fig. III is a vertical section thereof on the line III—III, Fig. II looking in the direction of the arrows.

Fig. IV is a plan view of the lower member of the burner shell.

45 Fig. V is a plan view of a burner involving the invention under a slight modification.

Fig. VI is a section thereof on the line VI—VI, Fig. V looking in the direction of the arrows.

50 Referring first to Fig. I, 10 represents a tank such as is customarily used for kitchen boilers, or water heaters. Its bottom, 11, is set up a considerable distance below its lower margin leaving a depending apron, 10^a, providing a chamber 12, in which is 55 located a so-called spreader, 14, the burner,

15, and a bent pipe the upper end of the longer vertical branch, 16, of which communicates with the bottom of the tank, the horizontal branch, 17, of which extends beneath the bottom of the burner, and the 60 shorter vertical branch, 18, of which extends upward through the burner and communicates with the bottom of the spreader, 14. The shell of the burner comprises a saucer-shaped bottom member, 19, and a top member or plate, 20, through which the jet orifices, 21, are formed. The bottom member of the shell has a radially disposed notch, 22, and a centrally disposed opening, 23, 65 through which the supporting pipe, 18, 70 passes centrally. The opening, 23, is of larger diameter than the pipe, 18, so as to leave around the pipe an opening for the passage of air for supporting combustion and this adds materially to the efficiency of 75 the burner.

The opening, 23, is bounded by the inner wall, 24, of the bottom member, 19, of the burner shell. This inner wall, 24, is of C-shape and its ends join the inner ends of the side walls, 25, of the notch, 22, and the outer ends of these walls, 25, in turn, join the ends of the C-shaped outer wall, 26, of the bottom member of the shell. These walls, 24, 25 and 26 join the bottom, 27, and 80 result in a hollow shell having in its top a C-shaped depression, 28. The walls, 25, of the notch, 22, are continued inward in the form of a U-shaped yoke, 29, the bend of 85 which embraces the front side of the supporting pipe, 18, and prevents the burner from moving rearward relatively thereto beyond a position concentric therewith. The forward movement of the burner relatively 90 to the pipe beyond this concentricity is prevented by a bar, 30, which lies against the rear side of the pipe, 18, and has means for engaging the burner shell. Any suitable 95 means may be used for this purpose. Preferably the bar has at its ends down-turned 100 legs, 31, which occupy sockets in the burner shell. Preferably these sockets consist of perforations, 32, formed through the jet plate, 20, and these perforations may be formed through the plate opposite the depression, 28, of the shell, so that the legs, 31, project downward into the interior gas chamber, 28, of the burner, as shown in 105 Figs. V and VI, or they may be formed through portions, 20^a, in the form of lugs 110

or projections which extend from the inner margin of the plate and project over the central opening, 23, of the shell, as shown in Figs. II and III. This latter arrangement has the advantages over the former in that the bar is not subjected to such an intense destructive heat and the lower ends of its legs are not subjected to an upward pressure of the gas that would tend to lift them free of their sockets and permit the bar to become dislodged. With the arrangement shown in Figs. V and VI, the bar will fit between the nipples of the burner and the nipples that engage the rear side of the bar 15 will assist in preventing the burner from moving forward relatively to the pipe, 18.

The jet plate may be conterminous with the outer surfaces of the walls, 24, 25 and 26 of the bottom member, 19, of the shell 20 and rest flat upon top of them as shown in Figs. V and VI or the said walls may be rabbeted at top as shown at 33, and the margins of the plate, 20, fitted in said rabbets as shown in Figs. II, III and IV. In any 25 event the top and bottom members of the shell are firmly secured together by bolts, 34.

Gas is admitted to the interior of the burner through openings, 35, formed through the bottom, 27, at points that are 30 diametrically opposite each other and equidistant from the notch, 22. These openings communicate with the rear ends of passages, 36, which are formed in ribs that are formed on the under side of the bottom, 27, during 35 the process of casting the bottom member, 19. The forward ends of these passages, 36, communicate with the interior of a hollow spud, 37, which is formed on the front of the bottom member, 19, of the shell at a 40 point diametrically opposite the notch, 22, and equidistant from the openings, 35. The discharge branch of the mixer, 38, communicates with this spud, whence the gas passes in equal volumes through the passages, 36, 45 and is discharged through the openings, 35, into the burner, where it is equally distributed. This effectually prevents back firing, this prevention being due partly to the even distribution of the gas within the burner, 50 partly to the tortuous course of the gas passage—first upward through the spud, 37, thence horizontally through the passages, 36, and thence upward through the openings, 35, and partly to the comparatively 55 great length of the passages, 36. It is found in practice that even if the flame should succeed in passing back through the openings, 35, it is smothered in the passages, 36, before reaching the mixer, or even the 60 spud, 37.

What we claim as new is:

1. A burner having a hollow shell, said shell having an opening extending through it from top to bottom and adapted to re-

ceive a vertical support, said shell having 65 also a radial notch extending from its periphery to said central opening, means carried by the burner-shell and adapted to engage one side of said support for preventing the burner from moving in one direction 70 relatively to said support, and a bar adapted to engage the opposite side of said support for preventing the burner from moving in the opposite direction, said bar and the burner-shell having an engaging means 75 for preventing them from relative movement from normal relative positions.

2. A burner having a hollow shell, said shell having an opening extending through it from top to bottom and adapted to receive a vertical support, said shell having 80 also a radial notch extending from its periphery to said central opening, the walls of said notch being extended inward in the form of a U-shaped yoke, the curved portion of which is adapted to engage one side of said support for preventing the burner from moving in one direction relatively thereto, and a bar adapted to engage the opposite side of said support for preventing the burner from moving in the opposite direction relatively thereto, said bar and burner-shell having engaging means for preventing them from relative movement 85 from normal relative positions.

3. A burner having a hollow shell comprising a bottom member and a top member in the form of a plate having jet openings, said shell having an opening extending through it from top to bottom and adapted to receive a vertical support, said shell having also a radial notch extending from its periphery to said central opening, a bar adapted to engage the rear side of said central support and having downwardly extending legs, the burner shell having sockets into which said legs extend.

4. A burner having a hollow shell, said shell having an opening extending through it from top to bottom and adapted to receive a vertical support, said shell comprising a bottom member having a concavity in its top side and a top member having jet openings communicating with said concavity, the top member having portions extending inward over said central opening of the bottom member and having sockets or openings through it and a bar engaging the rear side of said support and having legs occupying the openings or sockets of the top member of the shell.

5. A burner having a hollow shell comprising a bottom member having through it a central opening and a radially disposed notch extending from the periphery of said hollow shell to said central opening, means carried by the shell and engaging one side of the central support for preventing the

shell from moving in one direction relatively thereto, and means engaging the opposite side of said support and also the shell of the burner for preventing the shell from moving in the opposite direction relatively to said support.

6. A burner of the class described comprising a bottom member having substantially C-shaped inner and outer walls leaving between them a substantially C-shaped chamber or depression, a top member having jet openings, said top member being substantially conterminous with the space bounded by the concentric inner and outer walls of the bottom member and having also portions which extend inward beyond the inner wall of the bottom member and are provided with sockets or perforations, and a bar engaging the front side of said support and having down-turned legs which

extend into or through the sockets in the aforesaid projecting portions of the top member of the shell.

7. A burner having a bottom member provided with a substantially C-shaped inner cavity or gas space, openings extending through the bottom of said cavity and disposed diametrically opposite each other so as to equally divide the spaces of said cavity on their opposite sides, said bottom member having equal passages which communicate at their rear ends with said openings and at their forward ends with an opening with which the outlet of the mixing chamber communicates.
